AMOS VERNER JENSEN, OF CEDAR FALLS, IOWA, ASSIGNOR TO VIKING PUMP COMPANY,
OF CEDAR FALLS, IOWA

ROTARY PUMP

Original application filed October 21, 1929, Serial No. 401,191. Divided and this application filed August 23, 1930. Serial No. 477,333.

My invention relates to improvements in rotary pumps and motors, and the object of my improvement is to provide release means for entrapped liquids in such devices

5 to reduce wear of the rotating parts, reduce power consumption, increase mechanical efficiency of the device, and prevent possibility of tooth fracture caused by excessive hydraulic pressures from liquid imprisonment at certain places within such devices.

Another object is to supply in such pumps and motors which have intermeshing rotary pistons, wholly separated relief passages in the casings, whereby in their coaction the 15 pistons maintain a regular delivery of liquid through the casing in each case without interference entrapping of the liquid acted upon by either piston.

This application is a division of my Patent No. 1,799,237, granted April 7, 1931, for rotary pump.

I have accomplished the above objects in said devices by the means which are hereinafter described and claimed, and which 25 are illustrated in the accompanying drawing, in which Fig. 1 is an elevation of a rotary pump with its face-plate removed, having intermeshing pistons therein and having casing recesses or passages for co- 30 operation with the pistons independently of each other for preventing entrapping of liquid in transit from a receiving to a delivery port. Fig. 2 is a like elevation, showing the same elements but having a modified arrangement and shape of each of the separated passages in the casing.

It is to be understood, that the above exemplifications are illustrative only of the invention, and that other modifications may 40 be effected in the elements of the device shown which will accomplish my said purposes, without departing from the invention.

In the pumping device shown, in both 45 cases, the numeral 1 denotes a pump cylinder

having an open front with marginal face 2 in one plane having screw holes 3 to receive screw fastenings from a face-plate not shown.

The rotary pumps of said figures are alike 50 in construction, except their inner wall passages which coact with their intermeshing pistons separately, and have the opposite receiving and discharge ports 6 and 5 located medially. In the interior chamber 4 ranged 55 along the longer diameter of the casing are the like pistons 15 having intermeshing projections hereinafter termed teeth 9, and mounted fixedly upon shafts 7 and 8, of which one may be power driven. In this type 60 of pump the teeth mesh in such a manner that the root closed cavities between them are alternately shifted from one piston to the other, so that a like but reversed pair of relief passages 11 are employed in the abutting 65 casing wall to successively and alternately receive liquid imprisoned in said cavities. The only difference between the passages 11 of said Figs. 1 and 2 is in the fact that the passages in the device of Fig. 1 are 70 adapted to deliver liquid to a neutral area and conveyed to the discharge port 5, the device being reversible and therefore functions the same regardless of the direction of 75 pump rotation.

The passages 11 in Fig. 2 are similar to those shown in Fig. 1, having each an annular part 11, which centrally aligned but separated parts 12 from the other passage in each instance, but the outer and T-headed 80 parts 14 of Fig. 1 are diametrically aligned with the parts 12, whereas in Fig. 2 the corresponding parts 14 are at a right angle to the said longer diametrical line of the casing, with angular outer terminations as shown, 85 connected to the annular parts 11 by narrow parts or necks 13. The passages in Fig. 2 are thus contrived, shaped and employed only where the rotations of the pistons are 90 unidirectional to deliver to one outlet. In

Fig. 1, the arrangement is such, that the ports 6 and 5 respectively become either receiving or discharge ports reversibly, when the direction of rotation of the pistons is reversed.

5 It is obvious that the neutral areas for reception of liquid from the root cavities may be positioned as desired relative to the different elements in coaction, and such relief means may be used with any rotary 10 pump or motor without departing from my invention:

In practice, the pistons being in positive rotation, their meshed arrangement and coaction causes liquid to be drawn into the

15 neutral area of the interior 4 of the casing to fill it, and be passed along between the teeth of the pistons to the opposite part of the chamber to be delivered by way of the discharge port 5. However, in case no relief passages 11, 12 and 14 are provided, the practically incompressible liquid becomes trapped as shown in Fig. 1 for instance between an end of an entrant tooth 9 of one piston 15 and the root cavity receiving said 25 tooth of the other piston. A relatively great pressure is thus transmitted from the tooth 9 in question, by way of the entrapped liquid, to the piston 10 and its pintle 8 and in reaction to the other pintle or shaft 7, exerting excessive friction on the pintles, and liable to cause breakage of the teeth.

Under normal conditions a good rotary pump of the ordinary type has a volumetric efficiency of from approximately 90 to 96 30 per cent, the balance being lost due to what is termed "slippage". A part of this "slippage" is due to the fact that the interdental spaces receiving liquid from the suction port of the pump do not become 100 per cent 40 filled. This is due to the fact that most rotary gear pumps usually must take liquid into the rotating elements against opposing centrifugal force. The interdental spaces therefore which are receding from the suction port contain the larger per cent of liquid 45 leaving a vacuum. Upon exposure to the discharge port the existing liquid pressure therein replaces the small spaces formerly occupied by the vacuum and intermeshing of 50 the piston teeth begins, whereby the liquid is expelled into the discharge port excepting for the balance of the small percentage termed as "slippage" that becomes trapped between the teeth which are intermeshing, 55 causing hammering, excessive wear, much loss of driving power, noise, vibration, and sometimes actual tooth fracture. The liquid then escapes into the suction opening.

In my device, the liquid is led from the 60 points where trapping occurs to a neutral area connecting with the tooth spaces that have just receded from the suction opening and which are not completely full, thereby permitting the liquid to pass thereinto at a 65 much reduced pressure which greatly dimin-

ishes the objectionable characteristics previously mentioned.

Comparative tests between rotary pumps supplied with such passages as above described, prove that such passages serve to 70 greatly enhance the efficiency of the devices in different ways. These tests show that the pumps supplied with these passages require eleven and three quarters per cent less operating power than the unsupplied pumps. 75 Noise, vibration and hammering are immediately greatly reduced and possibility of tooth fracture for the aforesaid reasons made very remote.

Furthermore, in pumps handling very viscous liquids such as tar, glucose, malt syrups and lacquers which naturally resist movement, the spaces between the teeth of the rotating elements receding from the suction opening contain a greater percentage of vacuum than ordinarily, due to the movements of the pistons not allowing sufficient time for the spaces to become completely filled with such heavy slow moving liquids. Consequently, the filling of these vacuum pockets at the discharge opening occurs with a decided impact setting up a very injurious vibration throughout the pump and piping system. This naturally rapidly wears out and dislocates the device. However, in my device, due to the relief passages the vacuum pockets are almost completely absent, greatly diminishing such harmful action as described.

As will be noted in Fig. 1, the outer terminations 14 of the relief passages because of their T-head shape, are never completely spanned or covered by any one tooth of a piston gear. The same applies to the device of Fig. 2. The relief passages thus may always discharge to a neutral area in receiving at their inner ends 12. The passages are not in direct communication with each other at their inner ends 12, but spaced apart and thus each passage is used alternately, and no 110 crowding is possible.

Having described my invention, what I claim as new, and desire to secure by Letters Patent, is:

In a rotary pump or motor, an elongated casing having an inlet port and a discharge port and having arcuate opposite walls, like intermeshing piston gears rotatably mounted in the casing to contact with said arcuate walls circumferentially, the meshing teeth of said gears leaving an intermediate space containing liquid under compression, one side wall of the casing having an annular cavity around each gear axis with radial extension in each case to effect a communication with said gear teeth spaces in turn, and each annular cavity having another radial extension at an angle to the first mentioned extension thereof, with each second mentioned radial extension having an angularly directed ter-

5 minal part extending opposite to the forward direction of rotation of the gear above it, said angularly directed part being longer across each passing tooth of a gear than the trans-
verse width of the tooth to deliver from said annular cavity into the inlet-port end of the casing by way of the trapped spaces in turn between teeth of said gear which are in terminal contact with the adjacent arcuate wall
10 of the casing.

In testimony whereof I affix my signature.
AMOS VERNER JENSEN.
